RESCUE LADDER

Milton J. Corwin, 2511 Castle Heights Ave.,
Los Angeles, Calif. 90034

Filed July 12, 1968, Ser. No. 12,720

Term of patent 14 years

Int. Cl. D6—01

U.S. Cl. D15—8

FIG. 1 is a front elevational view of the rescue ladder employing the new design;

FIG. 2 is a side elevational view of the rescue ladder; and

FIG. 3 is a top plan view of the rescue ladder.

I claim:

The ornamental design for a rescue ladder, substantially as shown.
